DISPLAY AND DISPENSING DEVICE FOR
RIBBONS AND THE LIKE

Edgar F. Welch, Columbus, Ohio

Application February 25, 1935, Serial No. 7,997

4 Claims. (Cl. 242—55.3)

This invention relates to devices for displaying and dispensing ribbons and other similar articles of merchandise that are produced and sold in long strips and are and may be wound in bolts or rolls. It is quite desirable that such merchandise shall be displayed to customers as they walk through the aisles of a store and that they may be examined by an intending purchaser without the necessity of opening boxes or pulling out drawers by the salesperson thereby wastefully consuming the time and energy of both parties.

The object of my invention, generally, therefore is to provide an improved displaying and dispensing device in which the intending purchaser can make a selection of the article desired without, at first, consulting the salesperson and even while the latter is serving another customer and then such intending purchaser quickly supplied by the salesperson when the latter has been released from the preceding customer. Other special objects will appear from the disclosure herein.

The invention is embodied in a device such as herein shown and described by means of which ribbons or the like are displayed in a suitable group of varying colors and if desired in various widths as well as colors at the aisle side of a store counter and when a selection has been made the length desired quickly withdrawn from the device, measured and cut off behind the counter.

In the accompanying drawing illustrating a structure according to the invention—

Figure 1 is a view in end elevation.

Fig. 2 is a plan view with parts broken out and one ribbon roll removed.

Fig. 3 is a detail in section showing two spool holders with one spool in section in one of the holders.

Fig. 4 is a detail view showing some of the tension devices for restraining the loose ends of the ribbon.

Fig. 5 is a sectional view of the tension device on a larger scale.

Fig. 6 is a detail in section on a larger scale of the construction of the anti-friction rollers on the cross bars for supporting the ribbon.

In the views 9 designates the store counter. The character 10 designates the base of the device which is preferably wood and of rectangular form. To each of the opposite ends of the base is secured a vertical frame member 11, 11 of metal of bar form bent from the top of the rear as a double incline. These frame members are of substantially identical form and size and are secured together in parallel relation to each other by three bars 12, 13, and 14. The bars 12 and 14

are each provided with a series of short tubes constituting anti-friction rollers 15 interposed between adjacent ends of which, as shown, are perforated disks 16 of larger diameter than the rollers said disks constituting spacers or heads to separate and guide the ribbons passed over the rollers and the plain bar 13.

The character 17 designates one of the rolls of ribbon. Each of these rolls has a center hub or spool 18 that at its opposite ends frictionally but 10 rotarily engages projections of holders 19. Said holders 19 are of spring sheet metal secured to the base 10 by screws so that the ribbon can be 15 unwound from the roll by draft on the free end.

At the selling or rear side of the base 10 there 15 is provided a tension device 20 for the free end of each ribbon between which tension device and the base the ribbon emerges from the display device, a small protruding end portion of the ribbon being left each time a piece is severed to permit 20 taking with the fingers of the hand for a fresh pull. Said tension device includes a pad of felt or rubber held in a metal clamp of suitable weight and each tension device is individual to a roll of 25 the ribbon. The device 20 is loosely supported 20 between vertical pins 20^a so that it can be lifted out.

In supplying the display device with a set of rolls of ribbon the loose end of each roll is passed, as shown, by full and broken lines, up over a 30 roller on bar 12, and over plain bar 13, over a roller on bar 14 and finally under the tension device 20. If by reason of sales the ribbon of any individual roll or bolt becomes exhausted it can be easily and quickly replaced with a fresh one 35 by the salesperson.

To protect the rolls of ribbon from falling dust and also to provide a surface over and above which the ribbons travel and are exposed for examination at the aisle side of the counter there 40 is provided a hood 25 of sheet metal extending over the top and front of the display device from the end frame to end frame, said cover being attached by spring clips 25^a adapted to removably 45 engage said end frames. I intend that the outer surface of said hood 25 should be painted white so as to aid the customer in judging the texture and by contrast with it the color or shade of the ribbon desired. Because the ribbons are somewhat spaced from the cover 25 at its front, taking the ribbon with the fingers to test its "feel" 50 weight and color is facilitated.

The forms of the parts can be changed without departing from the gist of the invention as 55

claimed. The term "roll" used in the claims includes bolt, so called.

What I claim is:

1. A displaying and dispensing device for a roll of ribbon-like material including a frame having a front side for displaying the ribbon-like material, a rear side opposite said displaying side, and from which rear side the ribbon-like material is dispensed, and a base between said sides, means on said base for rotatably supporting a roll of ribbon-like material, guiding means in said frame for directing the free end portion of said roll of ribbon-like material upward at the rear side of said frame and thence downward across the displaying side of said frame and finally to the dispensing side of said frame.
2. A displaying and dispensing device for a roll of ribbon-like material including a frame having a front side for displaying the ribbon-like material and a rear side opposite said displaying side, and from which rear side the ribbon-like material is dispensed, means within said frame for rotatably supporting a roll of said material, and means within said frame for guiding the free end portion of said roll of material from the rear side of said frame across the display side of said frame and thence to the dispensing side of said frame, said roll supporting means including means tending to resist the unrolling of said material, and means located near the rear side of the device tending to restrain the withdrawal of the ribbon-like material at said side, whereby said material is normally left in a stretched condition at the display side of the device.
3. A displaying and dispensing device for a plurality of rolls of ribbon-like material including a frame having a front side for displaying the

ribbon-like material, and a rear side opposite said displaying side from which rear side the ribbon-like material is dispensed, means within said frame for rotatably supporting rolls of ribbon-like material, and means within said frame for guiding the free end portions of said rolls of material from the rear side of said frame across the display side of said frame and thence to the dispensing side of said frame, and a cover member for the display side of said frame having 10 its exterior side of white color over which said ribbons are drawn.

4. A displaying and dispensing device for a roll of ribbon-like material including a frame having a front side for displaying the ribbon-like material and a rear side opposite said displaying side from which rear side the ribbon-like material is dispensed, means within said frame for rotatably supporting a roll of said material, and means within said frame for guiding the free 20 end portion of said roll of material from the rear side of said frame across the display side of said frame and thence to the dispensing side of said frame, said roll supporting means including means tending to resist the unrolling of said material, and means located near the rear side of the device tending to restrain the withdrawal of the ribbon-like material at said side, whereby said material is normally left in a stretched condition at the display side of the device. 30
